UNITED STATES PATENT OFFICE.

MORTIMER E. COOLEY, OF ANN ARBOR, MICHIGAN, ASSIGNOR OF ONE-HALF TO G. FRANK ALLMENDINGER, OF ANN ARBOR, MICHIGAN.

SHREDDING-MACHINE.

SPECIFICATION forming part of Letters Patent No. 782,109, dated February 7, 1905.

Application filed May 11, 1903. Serial No. 156,560.

To all whom it may concern:

Be it known that I, MORTIMER E. COOLEY, a citizen of the United States, residing at Ann Arbor, county of Washtenaw, State of Michigan, have invented a certain new and useful Improvement in Shredding-Machines; and I declare the following to be a full, clear, and exact description of the invention, such as will enable others skilled in the art to which it pertains to make and use the same, reference being had to the accompanying drawings, which form a part of this specification.

This invention relates to shredding-machines, and has for its object a machine intended to produce shreds or thin strips of dough that are adapted to be afterward used in constructing what are known as "shredded-wheat" biscuits.

In the drawings, Figure 1 is a side elevation. Fig. 2 is a plan of the front end of the belt and of the pressure-roll. Fig. 3 is a cross-section of the belt. Fig. 4 shows a smooth belt with grooved pressure-roll. Fig. 5 shows a grooved belt with the corrugations made separate from the main body of the belt.

A indicates a frame on which there are mounted two rolls B and C on shafts *b* and *c*. These rolls are both smooth and are similar to large broad belt-wheels. Around them is stretched a belt D, preferably of steel, like that used for band-saws. The belt D is provided with grooves which run lengthwise of it on the external side thereof—that is, on the side which does not come in contact with the rolls B and C. A pressure-roll E, of smooth material, is held in suitable adjustable boxes *e* on the frame A, and a feed-hopper F is mounted above the tangential point of the belt D and the pressure-roll E. Brackets G support a stripper-comb H, that is held pivotally to the bracket and is held in engagement against the belt D by a weight K. One of the rolls, as the roll C, is adjustable with respect to the other and is provided with means for both adjusting and trammimg it. For this purpose the boxing in which the shaft *c* engages slides in a guide R, that forms part of the frame A and is actuated in its sliding motion by a screw *d*. The boxing *e* of

the pressure-roll E is arranged to be adjusted 50 by the same character of adjustment by screw *f*.

In the mouth of the hopper F is a force-feed wheel *g* on the shaft of the main driving-wheel *c'*. The main driving-wheel *c'* meshes 55 with a gear-wheel on the shaft of the roll B.

Instead of a plain roll E and a corrugated belt D a grooved roll E' is used in connection with a smooth belt D'. The belt D' is constructed with a smooth body K and with attached strips *j*, such construction being used to overcome difficulties of construction of the tempered-steel belt D. 60

What I claim is—

1. In a shredding-machine, the combination 65 of parallel rollers, means for varying the distance between them, a flexible belt traveling on said rollers, said belt being grooved longitudinally and externally, and a pressure-roll engaging against the belt and a stripper 70 engaging against the belt, substantially as described.

2. In a shredding-machine, the combination 75 of an endless belt grooved longitudinally and externally thereof, means for carrying it, means for actuating it, and a pressure-roll whose axis is transverse to said belt, engaging closely against the high parts of the surface thereof, substantially as described.

3. In a shredding-machine, the combination 80 of a belt grooved longitudinally and externally, rolls on which the belt is carried, means for adjusting the rolls, a pressure-roll engaging against the belt, and a stripper engaging against the belt, substantially as described. 85

4. The combination of a belt grooved longitudinally and externally, means for supporting and actuating the belt, a pressure-roll engaging against the belt, a feeding device, and a stripper engaging against the belt, substantially as described. 90

In testimony whereof I sign this specification in the presence of two witnesses.

MORTIMER E. COOLEY.

Witnesses:

JAMES H. WADE,
GEORGE D. WILLCOX.
